ABSTRACT: A roller bed serves to receive the tube section stacks from a feeder conveyor. A movable transfer rake has tine rods which are about as long as the rollers of the roller bed and in one end position extend between the rollers of the roller bed. The rake is movable relative to the roller bed in a vertical direction to take over the stacks and subsequently in a substantially horizontal direction to its other end position. A stripper is movable to a position behind the stack of tube sections lying on the transfer rake above the stack magazine and remains in stripping position during the return movement of the transfer rake.

APPARATUS FOR AUTOMATICALLY CHARGING A
STACK MAGAZINE OF A BAG-MAKING MACHINE
WITH TUBE SECTION STACKS

Bag-making machines for making bags from tube sections are provided with stack magazines, into which stacks of tube sections must be continually placed during the operation of the machine. These stacks of tube sections have previously been placed into the stack magazines by hand. In view of the high-output rates of modern bag-making machines, a plurality of operators are required to place new stacks of tube sections into the stack magazine of the machine. This operation is difficult and must be performed with great care because the stacks of tube sections have a heavy weight in view of the large dimensions of the tube sections which are required for the manufacture of bags and great care is required during the manual handling of the stacks of tube sections and particularly as they are placed into the stack magazine if a relative shifting of the tube sections, which are loosely superimposed in the stack, is to be avoided. A shifting of the tube sections during manual handling is particularly liable to occur if the bags are made from smooth material, particularly plastics material sheeting. Owing to the high flexibility and large dimensions of the tube sections, the repositioning of shifted tube sections requires a large time. Shifted tube sections which are not repositioned will result in trouble in the operation of the bag-making machine and in bags which must be rejected.

It is an object of the invention to eliminate these disadvantages in the charging of stack magazines with stacks of tube sections in that apparatus for automatically charging the stack magazine is provided to perform the work previously carried out by the operators.

The apparatus according to the invention is characterized by a roller bed for receiving the tube section stacks from a feeder conveyor, a movable transfer rake having tine rods, which are about as long as the rollers of the roller bed and which in one end position extend between the rollers of the roller bed, the rake being movable relative to the roller bed in a vertical direction to take over the stacks and subsequently in a substantially horizontal direction to its other end position, in which the rake is disposed above the stack magazine, and a stripper which is movable to a position behind the stack of tube sections lying on the transfer rake above the stack magazine and which remains in stripping position during the return movement of the transfer rake.

The apparatus according to the invention can be used to take over stacks of any desired number of exactly aligned tube sections, which stacks have been formed at the discharge end of a tubing extruder and may have any desired dimensions, to feed these stacks to the stack magazine of the bag-making machine and to deliver the stacks to said magazine, without an unpermissible shifting of individual tube sections in the stack. The transfer capacity of the apparatus is sufficient for a charging even of high-duty bag-making machines with tube sections at the rate which is required for a continuous production by such machines. It will be understood that the apparatus is suitable for an automatic feeding of stacks of workpieces to other machines for processing flat workpieces.

In a development of the invention, the transfer rake is guided by guide rails, which are designed so that the transfer rake extends parallel to the rollers of the roller bed when the rake is disposed adjacent to said bed, and parallel to the bottom of the stack magazine when the rake is disposed adjacent to the stack magazine. In a preferred embodiment of the transfer rake, the tine rods thereof are secured by brackets extending at right angles to the tine rods to a common carrying bar, which at its ends is secured to lateral running gears, which have rollers rolling on the guide rails. This transfer rake is simple in design and may have a sufficiently large width in view of the often large lengths of the stacks of tube sections to be transferred. According another feature of the invention, the transfer rake is reciprocated between the roller bed and the stack magazine in a simple manner by a slider linkage having rocker arms provided with sliders, which slide in guide sleeves, which are pivotally mounted on the carrying bar.

According to another feature of the invention, the tine rods of the transfer rake are provided with rollers, which are rotatable in the longitudinal direction of the tine rods and which receive the stack of tube sections as the roller bed is lowered relative to the transfer rake. The rollers have the advantage that the stack of tube sections is stripped by the stripper from the transfer rake into the stack magazine of the bag-making machine without friction so that a relative shifting of the tube sections in the stack is also avoided.

10 The transfer of the stacks arriving on the roller bed to the transfer rake is controlled according to the invention by a stop, which extends parallel to the tine rods and which for an exact alignment of the stacks is adjustable transversely to the tine rods of the transfer rake, i.e., in the direction of travel on the roller bed, relative to the stack magazine to be fed, said stop being provided with a limit switch, which is disposed in the path of the stacks of tube sections arriving on the roller bed and deenergizes the means for driving the roller bed and at the same time energizes the reciprocating drive means for the roller bed to lower the same relative to the transfer rake. To ensure that the stack of tube sections engages the stop as smoothly as possible, it is another feature of the invention that the roller bed is adapted to be driven at two different peripheral velocities, the higher of which is equal to the delivery speed of the feeding conveyor delivering the stacks to the roller bed whereas the lower of said velocities is selected so that an excessively strong impact of the tube section stack on the stop is avoided. According to another proposal of the invention, the change of the roller bed drive to the lower speed and the deenergization are effected by means of a sensing lever, which is mounted on the described stop and disposed in the path of the stacks of tube sections arriving at the high speed of travel. Two switches are associated with the sensing lever. One of said switches is operated to change the speed of travel to the lower value when the stack is at a sufficiently large distance from the position in which it impinges on the stop. The other of said switches acts as a limit switch, which deenergizes the roller bed drive, now operating at a low speed, immediately before the stack impinges on the stop and which energizes the reciprocating drive means in the sense which has been described hereinbefore.

According to another proposal of the invention the transfer movement of the transfer rake fed with a stack of tube sections is initiated by a sensor, which senses the height of the stack in the stack magazine of the bag-making machine and initiates said transfer movement when the stack in the magazine has been used up in the bag-making machine but for a residue which is at least sufficient for a period of time which is equal to the period of time required to charge the stack magazine with a new stack of tube sections. This control of the transfer rake always ensures the correct charging of the stack magazine with a new stack before the supply contained in the magazine has been used up and without a formation of an excessively high stack in the magazine.

According to another feature of the invention, the forward and return movements of the transfer rake are limited by two limit switches, one of which terminates the forward movement 60 of the transfer rake to the stack magazine and at the same time energizes the reciprocating motor for the stripper to lower the same whereas the other limit switch terminates the return movement of the transfer rake to the roller bed and at the same time energizes said reciprocating motor to lift the stripper to its initial position and also energizes the reciprocating drive means for the roller bed to lift the same relative to the transfer rake and energizes the means for driving the rollers. This interlocked control ensures that the operation of the stripper and the return stroke of the roller bed so that it can 70 receive a new stack of tube sections will be performed in time.

In accordance with the invention, the up and down movement of the stripper is also controlled by two limit switches, one of which terminates the descent of the stripper to its stripping position and also energizes the drive motor for the transfer rake to return the same to the roller bed. This ar-

angement ensures that the transfer rake will be stationary, as required, during the descent of the stripper to its stripping position, and that the stripping

FIG. 3 is a top plan view showing the stop which is provided with a sensing lever and engageable by the stacks arriving on the roller bed.

The apparatus which is shown in the drawing comprises a rectangular frame 1. Guide rails 2, 2' are secured to opposite sides of the frame and like booms of a crane protrude beyond the base area of the frame. The guide rails consist of steel channels and are parallel to each other and secured to the frame in such a manner that the open sides of the channels face each other. The channels are angled, extending horizontally in the frame and being upwardly inclined outside the frame. As is apparent in FIG. 2, the height of the frame and the overhang of that portion of the guide rails 2, 2' which protrudes over the frame are selected in view of the receiving end of a bag-making machine 3 so that the protruding portions of the guide rails extend above a stack magazine 4 of a rotary feeder 5 of the bag-making machine 3 and approximately parallel to the bottom of the magazine.

A horizontal roller bed 6 is mounted in the frame 1 and can be lifted and lowered therein in such a manner that in the upper end position, indicated with dash-dot lines in FIG. 1, rollers 7 of the roller bed lie in one plane with feeder conveyors, such as roller beds 8, 8', which feed the stacks of tube sections formed at the discharge end of a tubing extruder, which is not shown on the drawing. The length and width of the roller bed 6 are, respectively, at least as large as the largest length and width of the tube sections or of the stacks formed by said tube sections. The rollers 7 are driven by known means, such as a drive belt, to rotate in the same sense. The roller drive can be switched between two roller speeds. Besides, the sense of rotation of the rollers can be reversed. The reciprocating drive means for the roller bed and the means for driving the rollers consist of known elements and are not shown in the drawing. The up and down movement of the roller bed is limited by two limit switches 9, 10, which are diagrammatically indicated.

Running gears 11, 11' have rollers 12, 12' running in the guide rails 2, 2'. A preferably round carrying bar 13 is secured at its ends to the running gears and extends throughout the width of the apparatus and parallel to the plane of conveyance defined by the roller bed 6. A multiplicity of tine rods 14, which are parallel to the rollers 7 of the roller bed 6, are secured to the carrying bar by means of depending brackets 15 extending at right angles to the tine rods 14. The parts 13, 14, 15 together form a transfer rake. The tine rods are regularly spaced along the carrying bar 13 by the same distance as the rollers 7 of the roller bed 6 but are staggered from the rollers 7 by one-half that distance so that the tine rods are aligned with the gaps between the rollers of the roller bed, as is shown in FIG. 1. The width of each gap between the rollers exceeds the width of the tine rods so that the rollers 7 can pass between the tine rods 14 during the up and down movement of the roller bed 6. The roller bed 6 and the transfer rake 13, 14, 15 are so related to each other that the rollers 7 protrude over the tine rods 14 when the roller bed 6 is in its upper end position, indicated in dash-dot lines in FIG. 1, and the rollers are below the tine rods when the roller bed is in its lower end position. The tine rods carry a multiplicity of small rollers 16, which protrude above the profile of the tine rod and rotate in the longitudinal direction of the tine rods.

The transfer rake 13-16 is movable on the guide rails 2, 2' by means of the running gears 11, 11'. As is apparent from FIG. 2, it assumes the end position indicated in solid lines adjacent to the roller bed 6 and the other end position, which is indicated in dash-dot lines, adjacent to the stack magazine 4. A slider linkage 17, 18, 18' is provided to reciprocate the transfer rake and comprises a crank 17, which is driven by a gear motor 19 and extends into a slot 20 (FIG. 2) of a rocker arm 18. The rocker arm 18 is secured to a shaft 21, which is parallel to the carrying bar 13 and rotatably mounted in the

machine frame. Another rocker arm 18', which has the same dimensions as the lever 18 and extends parallel to the rocker arm 18, is secured to the shaft 21. The two rocker arms carry sliders 22, 22', which slide in guide sleeves 23, 23', which are pivotally mounted on the round carrying bar 13 adjacent to the two running gears 11, 11'. The two end positions of the transfer rake 13, 14, 15 shown in FIG. 2 are controlled by two limit switches 24, 25, which are operated by a cam wheel 26, which is mounted on shaft of the crank 17.

10 A guide rod 27 which is parallel to the carrying bar 13 is secured to the two running gears 11, 11'. A holder 28 for a stop 29 is slidable on the guide rod 27 and can be fixed in position thereon. When the transfer rake 13, 14, 15 is in the end position shown in solid lines in the drawing, the stop 29 is disposed in the path of the tube section stacks 5 arriving on the roller bed 6 and is adjustable transversely to the tine rods 14, i.e., in the direction of travel on the roller bed 6. This stop permits of an exact alignment of the arriving stacks of tube sections relative to the stack magazine 4. A sensing lever 30 (FIG. 3) is rotatably mounted on the stop 29 and has a sensing arm, which is disposed in the path of the tube section stacks 5 arriving on the roller bed 6. Two switches 31, 32 are associated with the sensing lever. The switch 31 is a changeover switch, which is operable to change the means for driving the rollers 7 of the roller bed 6 from the high-delivery speed to a much lower conveying speed. This change is effected when the arriving stack of tube sections is spaced from the stop 29 by a safety distance x which is so large that it permits of a deceleration of the stack to the lower conveying speed. The switch 32 is a limit switch, which deenergizes the means for driving the rollers 7, now at a low speed, immediately before the stack of tube sections impinges on the stop. The changeover switch 31 may be omitted if the mass of the stack and the delivery speed of the stack are so small that there will be no undesirably strong impact on the stop.

Two bracket arms 33, 33' are secured to the guide rails 2, 2'. A stripper 34 extending between the guide rails is mounted on the bracket arms 33, 33' for an up and down pivotal movement. The stripper consists of two lateral lever arms 35, 35', each of which is rotatably mounted on one of the two bracket arms. The free ends of the lever arms are rigidly connected by a crossmember 36, to which a plurality of depending fingers 37 are secured. The arrangement of the stripper is such that in its upper end position, shown in solid lines, it is disposed outside the range of movement of the transfer rake 13, 14, 15 and in its lower end position, shown in FIG. 2, its fingers rest on the rear transverse wall of the stack magazine 4. As is apparent from FIG. 1, the fingers 37 are aligned with the gaps between the tine rods 14 and have such a small width that they can extend freely between the tine rods 14 of the transfer rake. The stripper is moved up and down by a reciprocating motor 39 and a lever 38. The up and down movement of the stripper is limited by two limit switches 40, 41.

45 A guide rod 42 (FIG. 2) is secured to the two bracket arms 33, 33'. A holder 43 for a reflecting photoelectric sensor 44 is horizontally slidable on the guide rod 42 and can be fixed in position thereon. The reflecting photoelectric sensor 44 is vertically slidable on a guide in the holder and can be fixed in position thereon. The photoelectric sensor emits a sensing ray 45 through the stack magazine 4 on a reflector 46, which is mounted on the rear wall of the magazine. The elevation of the photoelectric sensor may be adjusted so that the same 50 delivers a control pulse when the stack in the stack magazine from which the bag-making machine 3 is fed has any desired residual height y at which the light ray is no longer blocked.

55 The means for driving the various elements are interlocked as follows in order to ensure a proper sequence of operations in the apparatus:

70 a. The limit switch 25 terminates the forward movement of the transfer rake 13, 14, 15 to the stack magazine and at the same time energizes the reciprocating motor 39 to lower the stripper 34. b. The limit switch 40 terminates the descent of the stripper 34 to its stripping position and at the same time

energizes the drive motor 19 to return the transfer rake 13, 14, 15.

c. The limit switch 24 terminates the return movement of the transfer rake 13, 14, 15 and at the same time energizes the reciprocating motor 39 to lift the stripper 34, also energizes the reciprocating drive means for the roller bed 6 in the lifting sense and energizes the means for driving the rollers 7 of the roller bed 6.

d. The limit switch 32 which is carried by the stop 29 terminates the advance of the stack of tube sections on the roller bed 6 and at the same time energizes the reciprocating drive means for the roller bed to lower the same.

The mode of operation of the above-mentioned embodiment of the apparatus according to the invention will now be explained.

The apparatus will remain in its initial position, shown on the drawing, until the stack S_1 disposed in the stack magazine has been used up by the bag-making machine 3 to a residual height y so that the sensing ray 45 emitted by the reflecting photoelectric sensor 44 can reach the reflector 46. The photoelectric sensor 44 then initiates the cycle of operations of the apparatus by energizing the drive motor 19 to advance the transfer rake 13, 14, 15 along the guide rails 2, 2' to the end position shown in dash-dot lines so that the tube section stack S_1 disposed on the rake is carried to a position over the stack magazine 4. This advance is terminated by the limit switch 25, which deenergizes the drive motor 19 and at the same time energizes the reciprocating motor 39 to lower the stripper 34. The descending stripper engages the tube section stack resting on the transfer rake from the rear and the fingers 37 of the stripper move between the tine rods 14 and come to rest on the rear wall of the stack magazine 4. The limit switch 40 limits the descent of the stripper 34 and at the same time energizes the drive motor 19 to return the transfer rake 13, 14, 15. During the return movement of the transfer rake, the fingers 37 of the stripper hold the stack in position so that the same is stripped from the returning rake and received by the stack magazine. The freely rotatable rollers 16 carried by the tine rods ensure that the stack of tube sections slides without friction from the tine rods 14. The limit switch 24 limits the return movement of the transfer rake 13, 14, 15 in the initial position shown in solid lines and at the same time energizes the reciprocating motor 39 to lift the stripper 34, also energizes the reciprocating drive means for the roller bed 6 to lift the same, and energizes the means for driving the rollers 7 of the roller bed. This interlocked control causes the stripper 34 to be lifted to its initial position, which is shown in FIGS. 1 and 2 and in which it is stopped by the limit switch 41. At the same time, the roller bed 6 is moved from its lower end position, shown in solid lines, to its upper end position, shown in dash-dot lines, and the rollers 7 begin to rotate. In its upper end position, controlled by the limit switch 9, the roller bed is disposed on the same plane as the feeder conveyor 8, 8' and its rollers protrude above the supporting plane defined by the tine rods 14 of the transfer rake. The limit switch 9 opens a locking means, known per se, which is provided in the feeder conveyor 8, 8' so that the same delivers the next stack of tube sections to the roller bed, which advances said stack so that the same strikes the sensing lever 30 above the tine rods 14. The limit switch 31 associated with the sensing lever 30 now effects a change from the high-delivery speed to the lower conveying speed, at which the stack of tube sections is advanced as far as to the stop 29. Shortly before the stack reaches the stop 29, the sensing lever 30 operates the limit switch 32 to stop the rollers 7, render the locking means in the feeder conveyor 8 effective and energize the reciprocating drive means for the roller bed to lower the same. As the roller bed 6 descends, the stack comes to rest on the tine rods 14 of the transfer rake 13, 14, 15. The limit switch 10 terminates the descent of the roller bed and the entire cycle of operation of the apparatus, which is now again in its initial position.

The elevation of the sensing ray 45 is suitably selected so that the residual height y of the stack in the stack magazine is

so large that the time in which the residual stack y is used up by the bag-making machine is equal to the time required by the transfer rake 13, 14, 15 to move the stack thereon to the stack magazine and to strip the stack into the magazine. With that optimum setting of the photoelectric sensor 44 serving to initiate the cycle of operations of the apparatus, the stacks of tube sections may have the optimum height, which corresponds to the height to which the stack magazine can be filled.

If it is more desirable to deliver the stacks to the roller bed by the feeder conveyor 8' on the opposite side, e.g., for reasons of layout, it will be sufficient to reverse the sense of rotation of the rollers 7 of the roller bed and to secure the stop plate 29 to its holder in a position in which the stop plate 29 is turned through 180° and laterally offset by a suitable distance. The apparatus will then properly perform the above-described cycle of operation when the tube section stacks are delivered from the right.

20 The apparatus may be nondetachably connected to the bag-making machine to form a permanent part of the latter. The embodiment shown in the drawing is easily movable on floor rollers 47 and provided with locking means 48 by which it can be firmly but detachably connected to the machine frame of 25 the bag-making machine. This apparatus may be used in conjunction with each of a plurality of bag-making machines, as required.

We claim:

30 1. Apparatus for automatically charging a stack magazine of a bag-making machine with tube section stacks, characterized by a roller bag (6) for receiving the tube section stacks (S_1) from a feeder conveyor (8, 8'), a movable transfer rake (13, 14, 15) having tine rods (14), which are about as long as the rollers (7) of the roller bed and which in one end position extend between the rollers (7) of the roller bed (6), the rake being movable relative to the roller bed in a vertical direction to take over the stacks and subsequently in a substantially horizontal direction to its other end position, in which the rake is disposed above the stack magazine (4), and a stripper (34), which is movable to a position behind the stack of tube sections lying on the transfer rake (13, 14, 15) above the stack magazine and which remains in stripping position during the return movement of the transfer rake.

45 2. Apparatus as set forth in claim 1, characterized in that the transfer rake (13, 14, 15) is guided by guide rails (2, 2'), which are designed so that the transfer rake extends parallel to the rollers (7) of the roller bed (6) when the rake is disposed adjacent to said bed, and parallel to the bottom of the stack magazine (4) when the rake is disposed adjacent to the stack magazine.

50 3. Apparatus as set forth in claim 2, characterized in that the tine rods (14) of the transfer rake are secured to a common carrying bar (13) by brackets (15) extending at right angles to the tine rods and the carrying bar is secured at its ends to lateral running gears (11, 11'), which with their rollers (12, 12') roll on the guide rails (2, 2').

55 4. Apparatus as set forth in claim 2, characterized in that the transfer rake (13, 14, 15) is reciprocable by a slider linkage (17, 18, 18'), which has rocker arms (18, 18') carrying sliders (22, 22'), which slide in guide sleeves (23, 23'), which are pivoted on the carrying bar (13).

60 5. Apparatus as set forth in claim 1, characterized in that the tine rods (14) of the transfer rake (13, 14, 15) carry rollers (16), which are rotatable in the longitudinal direction of the tine rods and which receive the tube section stack (S_1).

65 6. Apparatus as set forth in claim 1, characterized by a stop (29), which extends parallel to the tine rods (14) and is adjustable in the direction of travel on the roller bed (6) and carries a limit switch (32), which is disposed in the path of the tube section stacks arriving on the roller bed and which deenergizes the means for driving the roller bed and at the same time energizes the reciprocating drive means to lower the roller bed relative to the transfer rake.

7. Apparatus as set forth in claim 1, characterized in that the roller bed (6) is adapted to be driven at two different peripheral velocities and the higher of said velocities is equal to the delivery speed of the feeder conveyor (8, 8') delivering the tube section stacks (St) to the roller bed whereas the lower of said velocities is selected so that an excessively strong impact of the tube section stack on the stop (29) is avoided.

8. Apparatus as set forth in claim 6, characterized by a sensing lever (30), which is mounted on the stop (29) and disposed in the path of movement of the tube section stacks (St) as they are delivered at the higher speed, and two switches (31, 32), which are associated with said sensing lever (30) and one of which (31) is operated to change the speed of travel on the roller bed to the lower value when the stack is at a sufficiently large distance (x) from the position in which it impinges on the stop (29), whereas the other switch is a limit switch and immediately before the tube section stack impinges on the stop deenergizes the means for driving the rollers (7) and at the same time energizes the reciprocating drive means for the roller bed to lower the same.

9. Apparatus as set forth in claim 1, characterized by a sensor (44, 45, 46), which senses the height (y) of the stack in the stack magazine (4) of the bag-making machine (3) and serves to initiate the transfer movement of the transfer rake (13, 14, 15) fed with a tube section stack (St), as soon as the stack in the magazine has been used up but for a residue.

10. Apparatus as set forth in claim 1, characterized in that the forward and return movements of the transfer rake (13, 14, 15) are limited by two limit switches (24, 25), one of which (25) terminates the forward movement of the transfer rake to the stack magazine (4) and at the same time energizes the reciprocating motor (39) for the stripper (34) to lower the same, whereas the limit switch (24) terminates the return movement of the transfer rake to the roller bed (6) and at the same time energizes said reciprocating motor to lift the stripper to its initial position and also energizes the reciprocating drive means for the roller bed to lift the same relative to the transfer rake and energizes the means for driving the rollers.

11. Apparatus as set forth in claim 1, characterized in that the up and down movement of the stripper (34) is limited by two limit switches (40, 41), one of which (40) terminates the descent of the stripper to its stripping position and at the same time energizes the drive motor (19) for the transfer rake (13, 14, 15) to return the same to the roller bed (6).

12. Apparatus as set forth in claim 1, characterized in that the sense of rotation of the rollers (7) of the roller bed (6) is reversible.

13. Apparatus as set forth in claim 1, characterized in that it is movable on rollers (47).
